FLAT PLATE IRONER

Jason Hurley, Chicago, Ill.

Application January 23, 1953, Serial No. 332,829

14 Claims. (Cl. 38—36)

This invention relates to flat plate ironers. A flat plate ironer as contemplated herein is a small portable type for home use and it includes a buck, a heated shoe, spring means for normally separating the buck and heated shoe, and control means including a handle for latching the heated shoe in engagement with the buck and for applying pressure between the heated shoe and buck. Such a flat plate ironer may take the form disclosed in copending application Serial No. 332,830, filed January 23, 1953, by Jason Hurley and Hans F. Trepte.

In such a flat plate ironer the material to be ironed is placed on the buck, and then the handle of the control means is manipulated to move the heated shoe into engagement with the material on the buck, to latch the heated shoe in such engaging position and to apply pressure between the buck and the heated shoe for ironing purposes. After the ironing operation is completed the handle of the control means is again manipulated to relieve the pressure between the buck and heated shoe and to release this latching means for permitting the heated shoe to be separated from the buck to expose the ironed material.

The successful operation of such a flat plate ironer is dependent upon the skill of the operator thereof and such skill is not usually prevalent in the case of housewives where the small portable ironers here contemplated would normally be used. Different materials such as wool, cotton, synthetics, etc. require different ironing times and extreme care must be exercised in this respect to prevent scorching or burning. Further, if the ironer is inadvertently left closed, serious damage and fire hazards may well be created.

The principal object of this invention is to provide an improved flat plate ironer wherein the aforementioned shortcomings and dangers are eliminated, wherein the flat plate ironer, when closed, is automatically opened after a predetermined time interval, wherein the time interval may be adjusted for the purpose of ironing different types of materials, wherein a timing means and its connections with the control means for controlling the same are simple in construction and operation and wherein the timing means is set and activated by the control means upon closing of the ironer.

Briefly, the flat plate ironer of this invention includes detent means for latching the control means in position to latch the heated shoe in engagement with the buck and to apply pressure therebetween when the ironer is closed. Timing means is operatively connected with the detent means for releasing the control means after a predetermined time interval to relieve the pressure between the heated shoe and the buck and to permit the heated shoe and buck to be separated by the spring means. The timing means is also operatively connected with the control means so that it is set and activated thereby when the control means is operated to close the ironer. The timing means is adjusted so that the predetermined time intervals may be regulated as desired. In

2

this way the ironer is automatically opened at desired predetermined time intervals following closing thereof.

Further objects of this invention reside in the details of construction of the flat plate ironer and in the cooperative relationships between the component parts thereof.

Other objects and advantages of this invention will become apparent to those skilled in the art upon reference to the accompanying specification, claims and drawings in which:

10 Figure 1 is a top plan view of the flat plate ironer of this invention.

Figure 2 is a vertical sectional view through the ironer taken substantially along the line 2—2 of Figure 1 and showing in dotted lines the raised position of the heated shoe.

15 Figures 3, 4, 5 and 6 are partial vertical sectional views illustrating different positions taken by the flat plate ironer during use thereof.

Figure 7 is an enlarged partial plan view of the flat plate ironer with portions thereof broken away for clarity.

20 Figure 8 is a vertical sectional view taken substantially along the line 8—8 of Figure 7.

Figure 9 is a side elevational view partly in section and looking from the right of Figure 7.

25 Figure 10 is a perspective view with portions broken away illustrating the detent means and the timing means shown in Figures 7, 8 and 9.

Referring first to Figures 1 and 2, the flat plate ironer of this invention is generally designated at 10. It includes a supporting frame 11 formed from a pair of substantially U-shaped tubes. Each tube has a lower long leg 12, a substantially semicircular portion 13 and an upper short leg 14. The two tubes are secured together as by welding and the lower long legs 12 thereof diverge to form a supporting base. The tubes 11 may be formed of any suitable material, such as steel or the like. The ends of the lower legs 12 of the tubes may be closed by plates 15 suitably welded in place and similarly the ends of the upper legs 14 of the tubes may be closed by a plate 16 suitably welded in place. Thus the supporting frame while being extremely rugged in construction is light in weight.

20 The lower legs 12 of the supporting frame 11 carry a pair of transverse tubes 17 which in turn carry a perforated plate 18 having a depending flange 19. The plate 18 is suitably secured to the tubes 17 and the tubes 17 are 40 suitably secured to the lower legs 12 as by welding to form an immovable buck carried by the supporting frame. This buck may be provided with suitable padding 20 and covering material 21 suitably held in place on the buck.

45 The flat plate ironer also includes a pivoted arm 24 which is formed from a pair of tubes 25. The tubes 25 are generally straight except that the rear ends thereof are curved downwardly as indicated at 26 so as to conform to the curvature of the supporting frame 11. The two tubes 25 are secured together in spaced apart relation by a pair of cross members 27 and 28, the cross members being suitably secured thereto as by welding. The two tubes 25 of the pivoted arm 24 straddle the short legs 14

50 of the supporting frame 11. The rear end of the pivoted arm 24 is pivoted to the supporting frame 11 adjacent the short upper legs 14 thereof by a transverse pivot pin 29 journaled in suitable bearings 30 carried by the tubes. The pivoted arm 24 is normally urged to an upper position as illustrated in dotted lines in Figure 2 by means of a spring. The spring includes portion 31 engaging under the pivoted arm 24, a portion 32 engaging the curved part 13 of the supporting frame and helical portions around the pivot pin 29.

55 The flat plate ironer also includes a shoe 36 which may be cast from aluminum or the like. The lower side of the shoe is smooth and performs the ironing function

and the upper side includes a plurality of ribs 37 for strengthening the shoe and for accommodating electrical heating elements 38. Electric current is supplied to the electrical heating elements 38 through thermostatic controls carried by the shoe 36 and responding to the temperature thereof. These thermostatic controls are adjustable and may be adjusted by manipulating control knobs 40. In this way the shoe 36 may be electrically heated to desired temperatures, and by manipulating control knobs 40 the temperature of the shoe may be varied for purposes of ironing different types of material.

As illustrated in Figures 1 to 6, the shoe 36 also carries a pair of studs 41 which extend upwardly therefrom and which are provided at the upper ends with heads 42. A bracket 43 has a pair of holes and cylindrical bosses for slidably receiving the studs 41. Upward movement of the bracket 43 with respect to the studs 41 is limited by the heads 42 of the studs. The bracket 43 is provided at its ends with a pair of upwardly extending ears 44 having slots therein. Springs 46 encompass the studs 41 and extend between the heated shoe 36 and the bracket 43. Thus, the studs 41 provide a lost motion connection between the heated shoe 36 and the bracket 43, and the springs 46 resiliently separate the bracket and the heated shoe to the extent allowed by the lost motion connection.

The heated shoe 36 also is provided with a plurality of lugs 47 for accommodating a cover 48 which is secured in place by screws 49 entering the lugs 47. The cover 48 may be made of sheet metal or the like and operates to enclose the electrical heating elements 38, the thermostatic controls and the lost motion connection between the bracket 43 and the heated shoe 36. The cover 48 is provided with openings for accommodating the control knobs 40 for the thermostats and the bracket 43.

The free end of the pivoted arm 24 rotatably carries a transverse shaft 52 by means of suitable bearings in the forward ends of the tubes 25. This shaft 52 is connected by arms 53 to a handle 54. The handle 54 is utilized for lowering the pivoted arm 24 and for rotating the shaft 52, the handle 54 having an upper position and a lower position. The shaft 52 is also received in the slots of the ears 44 of the bracket 43 so that bracket 43 is movably carried by the shaft 52, and hence, the free end of the pivoted arm 24. If desired, tension springs (not shown) may be located between the bracket 43 and the shaft 52 for resiliently maintaining the bracket 43 in an upper position with respect to the shaft 52. Because the heated shoe 36 is supported through the lost motion connection by the shaft 52, it may pivot about the shaft 52 so that when the heated shoe is lowered against the stationary buck, it will automatically align itself with respect to the buck.

The shaft 52 carries a cam 55 in the form of a box cam having an actuating slot 56 terminating in a slot 57 which is concentric with the axis of the shaft 52. A roller 58 carried by a rod 59 engages in the slots 56 and 57 of the cam 55. The rod 59 extends through and is guided by suitable holes in the cross members 27 and 28. The rear end of the rod 59 rotatably carries a cam follower 60 having a beveled periphery. This cam follower 60 is adapted to engage with a cam track 61 suitably secured to the plate 16 as by welding or the like. The cam track 61 has a V groove for receiving the cam follower 60. This cam track is provided with a low dwell so that when the cam follower is held in the low dwell as illustrated in Figures 5 and 6 the pivoted arm 24 is locked in its lower position.

The bracket 43 carries a pair of cam members 65 underneath the shaft 52, these cam members 65 being provided with cam surfaces 66. The cam surfaces 66 are adapted to be engaged by rollers 67 carried by a pair of cam actuators 68 suitably secured to the shaft 52. Thus, as the shaft 52 is rotated from the position illustrated in Figure 5 to the position illustrated in Figure 6, the rollers 67 operate on the cam surfaces 66 of the cam members 65 to move the bracket 43 downwardly for the purpose

of compressing the springs 46. This downward movement of the bracket 43 is permitted by the slots in the ears 44 of the bracket 43.

A latch member 71 is pivotally secured by a pivot pin 72 to the rod 59 and this latch member 71 is provided with a latch shoulder 73 for engaging the cross member 28 of the pivoted arm 24. When the shoulder 73 engages the cross member 28 as illustrated in Figure 3, rearward movement of the rod 59 while the pivoted arm 24 is raised is prevented. When, however, the pivoted arm 24 is moved to its lower position as illustrated in Figure 4, the rear end of the latch member 71 engages the cam track 61 for disengaging the shoulder 73 from the cross member 28 to allow rearward movement of the rod 59.

The pivoted arm 24 is preferably provided with a cover (not shown) for enclosing the same and the parts carried thereby. This cover may be secured to the pivoted arm in any suitable manner. The construction of the flat plate ironer thus far described is very much like that disclosed in the aforementioned Jason Hurley and Hans J. Trepte copending application.

In the operation of the flat plate ironer the pivoted arm 24 is normally maintained in the upper position as illustrated in Figure 3 and in dotted lines in Figure 2 by means of the spring 31, 32. When the pivoted arm is in this upper position the latch shoulder 73 engages the cross member 28 to prevent rearward movement of the rod 59 and hence, to prevent forward rotation of the shaft 52 and the handle 54. In this way the handle 54 is also maintained in its upper position. The handle 54 may be grasped to pull the pivoted arm 24 from its upper position as illustrated in Figure 3 to its lower position as illustrated in Figure 4 where the heated shoe 36 engages the buck. During this lowering of the pivoted arm 24, the shaft 52 and hence the handle are not rotated.

When the pivoted arm 24 reaches its lower position as illustrated in Figure 4, the latch member 71 engages the top of the cam track 61 to release the latch shoulder 73 from the cross member 28, thus freeing the rod 59. As the downward and forward pressure on the handle 54 is continued, the handle 54 moves forwardly and downwardly to rotate the shaft 52. As a result the cam 55 is rotated whereby the actuating slot 56 thereof forces the rod 59 rearwardly to cause the cam follower 60 to engage in the low dwell of the cam track 61, as illustrated in Figure 5. As a result the pivoted arm 24 is locked in its lower position. Because the cam follower 60 is beveled and the cam track is in the form of a V groove, lateral displacement of the arm 24 while in locked position is minimized.

At the time that the pivoted arm 24 is locked in its lower position as illustrated in Figure 5, the rollers 67 of the cam actuators 68 engage the cam members 65. Continued downward movement of the handle 54 from its intermediate position to the lower position forces the bracket 43 downwardly as illustrated in Figure 6. This compresses the springs 46 of the lost motion connection for applying spring pressure between the heated shoe and the buck. As is noted in Figure 6, the cam actuators 68 do not move over center so that the springs 46 tend to rotate the shaft 52 and hence the handle 54 from their lower positions toward their upper positions. Thus, it is necessary to maintain the handle 54 in its lower position during the ironing operation. In this respect the flat plate ironer here differs from that of the aforementioned copending application of Jason Hurley and Hans F. Trepte.

When the shaft 52 and the handle 54 are released, the shaft 52 is rotated and the handle is moved from the lower position as illustrated in Figure 6 to the position illustrated in Figure 5 by the springs 46. When in the intermediate position illustrated in Figure 5, the lever main spring 31, 32 resiliently urges the pivoted arm 24 upwardly to cause the roller 60 to ride out of

the low dwell in the cam track 61 and by reason thereof the cam follower 58 entering the actuating slot 56 of the cam 55 further rotates the shaft 52 and the handle 54 toward the upper position as illustrated in Figure 4 whereupon the pivoted arm 24 is moved upwardly to the position illustrated in Figure 3. Thus, when the shaft 52 and handle 54 are released, they are automatically rotated and the spring pressure between the heated shoe and the buck is released as shown in Figure 5, the locking means is released as shown in Figure 4 and the pivoted arm 24 is raised to its upper position as shown in Figure 3.

Referring now to Figures 7 to 10, there is disclosed a detent means and associated timing means for latching the pivoted shaft 52 and handle 54 in the lowered position as illustrated in Figure 6 when moved to that position. Following a time interval determined by the timing means the detent means is released to free the shaft 52 whereupon the flat plate ironer is automatically opened in the manner described above. Thus, the ironer may be manually closed and automatically latched in closed position and then following a predetermined time interval the ironer is automatically opened.

The detent means includes a sleeve member 75 suitably secured to the shaft 52 as by welding, the sleeve member 75 extending radially from the shaft 52. A latch member 76 is slidably mounted in the sleeve 75 and is urged outwardly by a spring 77. The detent means also includes a shaft 78 journaled for rotation in one of the tubes 25 of the pivoted arm 24. One end of this shaft 78 is cut in half along a diameter to provide a flat surface 79. This end of the shaft 78 provides a latch member for cooperating with the latch member 76 for maintaining the shaft 52 and the handle 54 in their lowered positions. The flat surface 79 is normally in a vertical position as illustrated in dotted lines in Figure 9 and may be rotated in a counterclockwise direction to the other dotted line position illustrated in Figure 9. When the end of the shaft 78 is in the rotated position, the latch member 76 engages over the top of the shaft as illustrated in dotted lines in Figure 9 and is maintained in that position. As the shaft 78 is subsequently rotated in a clockwise position to make the flat surface 79 substantially vertical, then the latch member 76 is released to free the shaft 52.

The shaft 78 carries a gear 80 which has a small solid portion 81. The teeth of the gear 80 mesh with teeth 83 on a rack 84 which is pivoted at 85 to a crank arm 86 suitably secured to the shaft 52. A spring 87 connected to the crank arm 86 and the rack 84 urges the rack teeth 83 into engagement with the teeth of the gear 80. The rack 84 is provided with a solid portion 88 adjacent the teeth 83 which engages the solid portion 81 of the gear 80 when the shaft 52 and the handle 54 are rotated to the lower position as illustrated in Figure 6. In this way the rack 84 is disengaged from the gear 80 at this position of the shaft 52. When the shaft 52 and handle 54 are in the upper position, the flat surface 79 on the shaft 78 is vertically arranged. When the handle is moved from the upper position to the lower position as illustrated in Figure 6, the rack 84 drives the gear 80 to rotate the shaft 78 in a counterclockwise direction as illustrated in Figures 8 and 9 wherein the flat surface 79 of the shaft 78 assumes the other dotted line position illustrated in Figure 9. At the same time the latch member 76 is moved up over the shaft 78, this being permitted by the spring 77, and is latched in that position as illustrated in Figure 9.

The gear 80 meshes with a gear 92 carried by a shaft 93 journaled in one of the tubes 25 of the pivoted arm 24. The outer end of the shaft 93 is reduced as indicated at 95 and rotatably carries a knob 94. The knob 94 is held in place on the reduced portion 95 of the shaft 93 by means of a screw 96. A spring 97 urges the knob 94 inwardly. The inner face of the knob 94 is provided with a plurality of recesses 98 which are adapted

to receive projections on a plate 99 carried by the tube 24. A torsion spring 100 has one end secured to the shaft 93 and has the other end secured to the knob 94. Thus, by rotating the knob 94 with respect to the shaft 93 the force of the spring 100 may be adjusted and the knob 94 is maintained in the desired adjusted position by the recesses 98 therein cooperating with the projections on the plate 99. The torsion spring 100 operates to rotate the shaft 93.

10 Rotatably mounted on the shaft 93 is a gear 104 which carries a pawl 102 by means of a pivot pin 103. A spring 105 urges the pawl 102 into engagement with the teeth of the gear 92. The gear 104 also engages with a gear 106 of a timer 107 also carried by the tube 25.

15 In the normal position of the detent means and the timer, when the shaft 52 and handle 54 are in the vertical position as illustrated in Figures 3 and 4, the flattened surface 79 of the shaft 78 is in a vertical position. The outer end of the rack 84 is engaging the teeth of the gear 80 and the solid portion 81 of the gear 80 is engaging the teeth of the gear 92 carried by the shaft 93. Thus, rotation of the shaft 93 by the spring 100 is at this time prevented. When the shaft 52 and the handle 54 are moved from the upper position as illustrated in Figures 3 and 4 to the lower position as illustrated in Figure 6, the rack 84 rotates the gear 80, and, hence, the shaft 78 in a counter clockwise direction as illustrated in Figures 8 and 9 through substantially 45°. At this time the spring pressed latch member 76 is moved up and over the shaft 78 as illustrated in dotted lines in Figure 9. At the same time the solid portion 81 of the gear 80 engages the solid portion 88 of the rack 84 to release the rack 84 from the gear 80. This counter clockwise movement of the shaft 78 does not cause rotation of the gear 104, the pawl 102 slipping during this movement. During this movement the spring 100 is also tightened. When the rack 84 is thus disengaged from the gear 80 the tightened spring 100 operates to rotate the shaft 93 in a counterclockwise direction, and, hence, the shaft 78 in a clockwise direction. During this rotation of the shafts 78 and 93 the pawl 102 drives the gear 104 which in turn also drives the timer 107. The timer 107 operates to retard the rotation of the shafts 78 and 93 by the spring 100. When the shaft 78 is rotated in this retarded fashion by the spring 100 to the position where the flat surface 25 79 becomes vertical, the latch member 76 is released whereupon the shaft 52 is released for the purpose of opening the ironer in the manner described above. As the shaft 52 is being rotated for opening the ironer, the rack 84 slips along the teeth of the gear 80 so that this rotation of the shaft 52 is in no way retarded. It is noted that the teeth 83 of the rack 84 are constructed for this purpose. By adjusting the knob 94 the tension of the spring 100 may be adjusted for regulating the predetermined time interval before the shaft 52 is released for 30 opening purposes.

40 If while the detent means are engaged for latching the shaft 52 and handle 54 in the lowered position, it is desired to open the ironer all that is necessary is to raise the handle 54. When this is done the latch member 76 is urged into the sleeve 75 so that the latch member may readily be released from the shaft 78. The solid portion 81 of the gear 80 operates to prevent winding the timing means beyond a predetermined amount even though the handle 54 may be "pumped."

45 While for purposes of illustration one form of this invention has been disclosed, other forms thereof may become apparent to those skilled in the art upon reference to this disclosure, and, therefore, this invention is to be limited only by the scope of the appended claims.

50 I claim as my invention:

55 1. In a flat plate ironer having a supporting frame, a buck carried by the frame, an arm pivoted at one end to the frame, a heated shoe carried by the free end of the pivoted arm above the buck, spring means normally

raising the pivoted arm and heated shoe to an upper position, the heated shoe being moved against the buck when the pivoted arm is lowered to a lowered position, latch mechanism for latching the pivoted arm in its lowered position, resilient means for applying pressure between the buck and heated shoe when the pivoted arm is latched in its lowered position, and control means including a handle and operatively connected with said latch mechanism and resilient means for operating said latch mechanism and resilient means, in combination therewith, detent means operatively connected with said control means for latching said control means to maintain said latch mechanism in position to latch the pivoted arm in its lowered position and to maintain said resilient means in position to apply pressure between the buck and heated shoe, time controlled timing means operatively connected with said detent means for releasing said control means after a predetermined time interval to release the resilient means for relieving the pressure between the buck and heated shoe and to release the latch mechanism for permitting the pivoted arm to be raised to its upper position by the spring means.

2. In a flat plate ironer having a supporting frame, a buck carried by the frame, an arm pivoted at one end to the frame, a heated shoe carried by the free end of the pivoted arm above the buck, spring means normally raising the pivoted arm and heated shoe to an upper position, the heated shoe being moved against the buck when the pivoted arm is lowered to a lowered position, latch mechanism for latching the pivoted arm in its lowered position, resilient means for applying pressure between the buck and heated shoe when the pivoted arm is latched in its lowered position, and control means including a handle and operatively connected with said latch mechanism and resilient means for operating said latch mechanism and resilient means, in combination therewith, detent means operatively connected with said control means for latching said control means to maintain said latch mechanism in position to latch the pivoted arm in its lowered position and to maintain said resilient means in position to apply pressure between the buck and heated shoe, time controlled timing means operatively connected with said detent means for releasing said control means after a predetermined time interval to release the resilient means for relieving the pressure between the buck and heated shoe and to release the latch mechanism for permitting the pivoted arm to be raised to its upper position by the spring means, and means operatively connecting the timing means and the control means for setting and activating the timing means when the control means is operated to operate said latch mechanism and resilient means.

3. In a flat plate ironer having, a buck, a heated shoe, spring means for normally separating the buck and heated shoe, and control means including a handle for latching the heated shoe in engagement with the buck and for applying pressure between the heated shoe and buck, in combination therewith, detent means operatively connected with said control means for latching the control means in position to latch the heated shoe in engagement with the buck and to apply pressure therebetween, and time controlled timing means operatively connected with said detent means for releasing said control means after a predetermined time interval to relieve the pressure between the heated shoe and buck and to permit the heated shoe and buck to be separated by the spring means.

4. In a flat plate ironer having, a buck, a heated shoe, spring means for normally separating the buck and heated shoe, and control means including a handle for latching the heated shoe in engagement with the buck and for applying pressure between the heated shoe and buck, in combination therewith, detent means operatively connected with said control means for latching

10 the control means in position to latch the heated shoe in engagement with the buck and to apply pressure therebetween, time controlled timing means operatively connected with said detent means for releasing said control means after a predetermined time interval to relieve the pressure between the heated shoe and buck and to permit the heated shoe and buck to be separated by the spring means, and means operatively connecting the timing means and the control means for setting and activating the timing means when the control means is operated to latch the heated shoe in engagement with the buck and to apply pressure therebetween.

15 5. In a flat plate ironer having a supporting frame, a buck carried by the frame, an arm pivoted at one end to the frame, a heated shoe carried by the free end of the pivoted arm above the buck, spring means normally raising the pivoted arm and heated shoe to an upper position, the heated shoe being moved against the buck when the pivoted arm is lowered to a lowered position, latch mechanism for latching the pivoted arm in its lowered position, resilient means for applying pressure between the buck and heated shoe when the pivoted arm is latched in its lowered position, and control means including a shaft and a handle and operatively connected with said latch mechanism and resilient means for operating said latch mechanism and resilient means, in combination therewith, detent means including a latch member carried by the shaft of the control means, a second shaft and a latch member carried by the second shaft, said latch members of the detent means engaging upon operation of the control means to maintain said latch mechanism in position to latch the pivoted arm in its lowered position and to maintain said resilient means in position to apply pressure between the buck and heated shoe, time controlled timing means operatively connected with said second shaft for disengaging the latch members after a predetermined time interval to release the resilient means for relieving the pressure between the buck and heated shoe and to release the latch mechanism for permitting the pivoted arm to be raised to its upper position by the spring means.

20 6. In a flat plate ironer having a supporting frame, a buck carried by the frame, an arm pivoted at one end to the frame, a heated shoe carried by the free end of the pivoted arm above the buck, spring means normally raising the pivoted arm and heated shoe to an upper position, the heated shoe being moved against the buck when the pivoted arm is lowered to a lowered position, latch mechanism for latching the pivoted arm in its lowered position, resilient means for applying pressure between the buck and heated shoe when the pivoted arm is latched in its lowered position and control means including a shaft and a handle and operatively connected with said latch mechanism and resilient means for operating said latch mechanism and resilient means, in combination therewith, detent means including a latch member carried by the shaft of the control means, a second shaft and a latch member carried by the second shaft, said latch members of the detent means engaging upon operation of the control means to maintain said latch mechanism in position to latch the pivoted arm in its lowered position and to maintain said resilient means in position to apply pressure between the buck and heated shoe, time controlled timing means operatively connected with said second shaft for disengaging the latch members after a predetermined time interval to release the resilient means for relieving the pressure between the buck and heated shoe and to release the latch mechanism for permitting the pivoted arm to be raised to its upper position by the spring means, and means operatively connecting the shaft of the control means, the timing means and said second shaft for activating the timing means and setting the second shaft when the control means is op-

erated to operate said latch mechanism and resilient means.

7. In a flat plate ironer having, a buck, a heated shoe, spring means for normally separating the buck and heated shoe, and control means including a shaft and a handle for latching the heated shoe in engagement with the buck and for applying pressure between the heated shoe and buck, in combination therewith, detent means including a latch member carried by the shaft of the control means, a second shaft and a latch member carried by the second shaft, said latch members of the detent means engaging upon operation of the control means for latching the same in a position to latch the heated shoe in engagement with the buck and to apply pressure therebetween, time controlled timing means operatively connected with said second shaft for disengaging the latch members after a predetermined time interval for releasing said control means to relieve the pressure between the heated shoe and buck and to permit the heated shoe and buck to be separated by the spring means.

8. In a flat plate ironer having, a buck, a heated shoe, spring means for normally separating the buck and heated shoe, and control means including a shaft and a handle for latching the heated shoe in engagement with the buck and for applying pressure between the heated shoe and buck, in combination therewith, detent means including a latch member carried by the shaft of the control means, a second shaft and a latch member carried by the second shaft, said latch members of the detent means engaging upon operation of the control means for latching the same in a position to latch the heated shoe in engagement with the buck and to apply pressure therebetween, time controlled timing means operatively connected with said second shaft for disengaging the latch members after a predetermined time interval for releasing said control means to relieve the pressure between the heated shoe and buck and to permit the heated shoe and buck to be separated by the spring means, and means operatively connecting the shaft of the control means, the timing means and said second shaft for activating the timing means and setting the second shaft when the control means is operated to latch the heated shoe in engagement with the buck and to apply pressure therebetween.

9. In a flat plate ironer having, a buck, a heated shoe, spring means for normally separating the buck and heated shoe, and control means including a handle for latching the heated shoe in engagement with the buck and for applying pressure between the heated shoe and buck, in combination therewith, detent means operatively connected with said control means for latching the control means in position to latch the heated shoe in engagement with the buck and to apply pressure therebetween, time controlled timing means operatively connected with said detent means for releasing said control means after a predetermined time interval to relieve the pressure between the heated shoe and buck and to permit the heated shoe and buck to be separated by the spring means, and means for adjusting the timing means to regulate the predetermined time interval.

10. In a flat plate ironer having, a buck, a heated shoe, spring means for normally separating the buck and heated shoe, and control means including a handle for latching the heated shoe in engagement with the buck and for applying pressure between the heated shoe and buck, in combination therewith, detent means operatively connected with said control means for latching the control means in position to latch the heated shoe in engagement with the buck and to apply pressure therebetween, time controlled timing means operatively connected with said detent means for releasing said control means after a predetermined time interval to relieve the pressure between the heated shoe and buck and to permit the heated shoe and buck to be separated by the spring means.

means, and means for regulating the temperature of the heated shoe and for adjusting the timing means to regulate the predetermined time interval.

11. In a flat plate ironer having, a buck, a heated shoe, spring means for normally separating the buck and heated shoe, and control means including a handle for latching the heated shoe in engagement with the buck and for applying pressure between the heated shoe and buck, in combination therewith, detent means operatively connected with said control means for latching the control means in position to latch the heated shoe in engagement with the buck and to apply pressure therebetween, time controlled timing means operatively connected with said detent means for releasing said control means after a predetermined time interval to relieve the pressure between the heated shoe and buck and to permit the heated shoe and buck to be separated by the spring means, means for adjusting the timing means to regulate the predetermined time interval, and means operatively connecting the timing means and the control means for setting and activating the timing means when the control means is operated to latch the heated shoe in engagement with the buck and to apply pressure therebetween.

12. In a flat plate ironer having, a buck, a heated shoe, spring means for normally separating the buck and heated shoe, and control means including a handle for latching the heated shoe in engagement with the buck and for applying pressure between the heated shoe and buck, in combination therewith, detent means operatively connected with said control means for latching the control means in position to latch the heated shoe in engagement with the buck and to apply pressure therebetween, time controlled timing means operatively connected with said detent means for releasing said control means after a predetermined time interval to relieve the pressure between the heated shoe and buck and to permit the heated shoe and buck to be separated by the spring means, means for regulating the temperature of the heated shoe and for adjusting the timing means to regulate the predetermined time interval, and means operatively connecting the timing means and the control means for setting and activating the timing means when the control means is operated to latch the heated shoe in engagement with the buck and to apply pressure therebetween.

13. In a flat plate ironer having a buck, a heated shoe, spring means for normally separating the buck and heated shoe, a latch mechanism for latching the heated shoe adjacent the buck, resilient means for applying pressure between the buck and the latched heated shoe, control means, including a handle, operatively connected to the latch mechanism and the resilient means for moving and latching the heated shoe adjacent the buck and for applying pressure between the buck and the latched heated shoe when the control means is manipulated in one direction by the handle and for relieving the pressure and unlatching the heated shoe to allow the spring means to separate the buck and heated shoe when the control means is moved in the opposite direction, in combination therewith, means operatively associated with said control means for maintaining said control means in position when it has been operated in said one direction, and means including timing means operatively associated with said control means for operating said control means in said opposite direction after a predetermined time interval.

14. In a flat plate ironer having a buck, a heated shoe, spring means for normally separating the buck and heated shoe, a latch mechanism for latching the heated shoe adjacent the buck, resilient means for applying pressure between the buck and the latched heated shoe, control means, including a handle, operatively connected to the latch mechanism and the resilient means for moving and latching the heated shoe adjacent the buck and for applying pressure between the buck and the latched heated shoe when the control means is manipulated in one direction by the handle and for relieving the pressure and un-

11

latching the heated shoe to allow the spring means to separate the buck and heated shoe when the control means is moved in the opposite direction, in combination therewith, means operatively associated with said control means for maintaining said control means in position when it has been operated in said one direction, means including timing means operatively associated with said control means for operating said control means in said

5

12

opposite direction after a predetermined time interval, and means operatively associated with said control means for setting and activating said timing means when said control means is operated in said one direction.
